UNITED STATES PATENT OFFICE.

ALANSON W. FARRINGTON, OF RANDOLPH, MASSACHUSETTS, ASSIGNOR TO FARRINGTON MANUFACTURING COMPANY, OF RANDOLPH, MASSACHUSETTS, A CORPORATION OF MAINE.

EYEGLASS-CASE.

No. 909,386.

Specification of Letters Patent.

Patented Jan. 19, 1909.

Application filed August 21, 1905. Serial No. 275,072.

To all whom it may concern:

Be it known that I, ALANSON W. FARRINGTON, of Randolph, in the county of Norfolk and State of Massachusetts, have invented certain new and useful Improvements in Eyeglass-Cases, of which the following is a specification.

This invention relates to boxes, and has particular reference to metal boxes comprising two members hinged together and provided with spring devices for holding the said members in either closed or open position.

The object of this invention is to provide a simple and durable spring connection, and one which shall be noiseless in its operation.

To these ends, the invention consists in the construction and combination of parts substantially as hereinafter described and claimed.

Of the accompanying drawings,—Figure 1 is a plan view of a box of the type commonly known as an eyeglass-case, the lid being open. Fig. 2 represents a section on line 2—2 of Fig. 1. Fig. 3 is a view similar to Fig. 2, but showing the lid as closed.

Similar reference characters indicate similar parts throughout the several views.

The two members of the box comprise the lower or body member 10, and the upper or cover or lid member 11, said two members being connected by hinges 12, which hinges may be constructed in any ordinary or preferred manner.

The member 10 is formed with a lug 13, which may comprise a rolled lip suitably formed to be engaged by one end of the link hereinafter described. Said lug 13 is not in alignment with the axis of the hinge 12, but is located below an imaginary line connecting the two hinges 12, as shown in Figs. 2 and 3.

The cover or lid member 11 is provided with ears 14, which are shown as comprising lips struck up from metal of the cover, and bent as shown, to engage the ends of a substantially straight spring 15. Said spring preferably consists of a piece of resilient wire, having its extreme ends bent or curved as indicated in Fig. 1, so as to prevent longitudinal movement of the spring relatively to the ears 14. In practice, however, the ears 14 are usually bent down upon the spring firmly enough to retain it permanently in its position against the under

side of the lid and parallel with the line of the hinges 12.

A link 16, which may consist of a strip of sheet metal, is bent at its ends to form a lower hook 17 to engage the lug 13 of the box member 10, and an upper hook 18, which embraces the middle portion of the spring 15. Said link is of such length that whether the box be opened or closed, the spring will be flexed or under such tension as to constantly exert a pulling action on the link.

As shown in Figs. 2 and 3, the construction of the parts and the positions or locations of the points of attachment of the link to the spring of one member of the box, and the lug of the other member of the box relatively to an imaginary line extending from one hinge 12 to the other hinge 12, is such as to permit the end 18 of the link to pass beyond the said imaginary line when moving from the position shown in Fig. 3 to that shown in Fig. 2. In other words, a plane intersecting the points indicated by 12 and 13 is crossed by the link when moving from one extreme position to the other as the box is opened or closed. In passing such line or plane, an imaginary line connecting the two ears 14 is necessarily at a greater distance from the lug 13 to which one end of the link is attached, and consequently the spring 15 exerts a greater tension when the lines 12, 13, and 14 are in one plane than when the end 18 of the link moves to either one of its extreme positions. Therefore, the spring and the link tend to keep the box closed or open, and yet under a yielding tension, so that the lid may be quickly snapped open or shut.

Obviously the positions of the parts might be reversed. In other words, the member 11 of the box might be the lower or body member, and the member 10 so formed as to constitute the cover or lid. Furthermore, it is to be understood that I do not limit myself to the particular form of box shown, since the invention may be embodied in other forms of eyeglass-cases, or other forms of boxes in general.

Having now described my invention, I claim—

1. A spring lid box comprising two members having a hinged connection, a spring formed of a single piece of resilient wire secured to one of said members, means for

- 5 preventing longitudinal movement of said
spring and a link connected to the other
member and free to move independently
thereof, said link engaging said spring at
a point intermediate of the ends of the latter
whereby the spring will exert a pulling action
upon said link.
- 10 2. A spring lid box comprising two mem-
bers having a hinged connection, one of said
members having ears struck up therefrom, a
spring formed of resilient wire the ends of
which are fastened beneath said ears, and a
link connected to the other member and free
to move independently thereof, said link en-
gaging said spring at a point intermediate
of the ends of the latter, whereby the spring
will exert a pulling action upon said link.

- 15 3. A spring lid box comprising two mem-
bers having a hinged connection, one of said
members having ears struck up therefrom, a 20
spring formed of a single piece of resilient
wire having its ends secured beneath said
ears, said ends being bent, and a link con-
nected to the other member and engaging
said spring at a point intermediate of the
ends of the latter, whereby the spring will
exert a pulling action upon the link.

25 In testimony whereof I have affixed my
signature, in presence of two witnesses.

ALANSON W. FARRINGTON.
